UNITED STATES PATENT OFFICE.

JOHN J. ISLER, OF KIPLING, MICHIGAN.

AIR-SPRING.

1,376,206.

Specification of Letters Patent. Patented Apr. 26, 1921.

Application filed April 2, 1920. Serial No. 370,721.

To all whom it may concern:

Be it known that I, JOHN J. ISLER, a citizen of the United States, and a resident of Kipling, in the county of Delta and State of Michigan, have invented a new and Improved Air-Spring, of which the following is a full, clear, and exact description.

This invention relates to improvements in air springs, an object of the invention being 10 to provide improved mounting for a pneumatic cushion which will entirely inclose the cushion and which will permit the latter to freely function to absorb shocks and vibrations and gives resilient support in any position in which it is used.

A further object is to provide an improved construction and arrangement of casing which will be substantially watertight to prevent injury to the cushion through contact with atmospheric conditions.

With these and other objects in view the invention consists in certain novel features of construction, and combinations and arrangements of parts as will be more fully 25 hereinafter described and pointed out in the claims.

The accompanying drawing is a view in longitudinal section illustrating my invention.

30 1 represents a cylinder having a base 2 with a projection 3 thereon for attachment of the cylinder to any suitable mount. The other end of the cylinder is open and is provided adjacent its open end with external 35 screw threads as shown at 4.

5 represents a plunger which fits within the cylinder 1 and is made with a rod 6 extending from the plunger any desired distance and adapted to be fixed to the parts 40 employed. The plunger 5 is in the form of an inverted cup having a cylindrical recess 7 in its inner face to receive the upper end of an air cushion 8. This cushion 8 comprises a tubular rubber or other elastic member having its upper end located in the recess 7 of the plunger 5 and maintained in cylindrical form by means of a disk or disks 9 around which the end of the cushion 8 is secured, and rings 10 and 11 are positioned 45 inside and outside of this upper end of the cushion and all of the parts are secured together by any suitable adhesive, and I preferably employ a surfacing of wax or other material to fill all of the openings or spaces

in the connection to prevent possibility of 55 air leakage.

The disk 9 and the plunger 5 are made with an air inlet port 12 and a screw plug 13 normally closes this port. When the plug 13 is removed, air under any desired pressure 60 may be admitted but under ordinary conditions atmospheric pressure or slightly in excess thereof is all that is necessary for the cushion.

The lower end of the cushion 8 is secured 65 around a disk or disks 14 and it will be noted that this disk 14 is of such size that it is necessary to expand or stretch the end of the cushion 8 to position the latter around the disk, and the combined diameter of the 70 disk and the cushion is substantially the same diameter as the internal diameter of the cylinder 1.

By reason of this construction, the wall of 75 the cushion 8 is spaced from the inner face of the cylinder 1 throughout the greater portion of the length of the cushion, thus permitting the cushion to freely expand laterally when compressed longitudinally without danger of cutting or otherwise injuring 80 the cushion by the movement of the plunger.

A cylindrical casing 15 constitutes an 85 enclosure for the device and is made with internal screw threads 16 to engage the screw threads 14 of cylinder 1 and permit the casing 15 to be screwed downwardly upon the cylinder until the lower end of the casing tightly engages the base 2. The upper end of the casing 15 is made with a bore 17 to receive the rod 6 and has a relatively close 90 fit with the rod but permits longitudinal movement of the latter. When this casing 15 is in position as clearly shown, the pneumatic cushion 8 is protected from water or from other weather conditions and hence, 95 the life of the device is greatly lengthened.

In operation, the plunger 5 moves longitudinally relative to the cylinder 1 and in this movement operates to compress the air 100 in the cushion 8, the walls of the latter expanding transversely when compressed longitudinally and operating as a pneumatic cushion to absorb shocks, jars, strains, etc.

Various slight changes might be made in 105 the general form and arrangement of parts described without departing from the invention, and hence I do not limit myself to the precise details set forth, but consider my-

self at liberty to make such changes and alterations as fairly fall within the spirit and scope of the appended claims.

I claim:

- 5 1. A device of the character stated, comprising a cylinder, a plunger in the cylinder, said plunger having a cylindrical recess in its inner end, a cylindrical pneumatic cushion in the cylinder, one end of said cushion secured in the recess of the plunger, and a disk secured in the other end of the cushion, said disk expanding the walls of the cushion and holding the walls of the cushion in contact with the inner face of the cylinder.
- 10 2. A device of the character stated, comprising a cylinder, a plunger in the cylinder, said plunger having a cylindrical recess in its inner end, a cylindrical pneumatic cushion in the cylinder, one end of said cushion secured in the recess of the plunger, a disk secured in the other end of the cushion, said disk expanding the walls of the cushion and holding the walls of the cushion in contact with the inner face of the cylinder.
- 15 3. A device of the character stated, comprising a cylinder, a plunger in the cylinder, said plunger having a cylindrical recess in its inner end, a cylindrical pneumatic cushion in the cylinder, one end of said cushion secured in the recess of the plunger, a disk secured in the other end of the cushion, said disk expanding the walls of the cushion and holding the walls of the cushion in contact with the inner face of the cylinder, and said cushion throughout the greater portion of its length having its walls spaced from the inner surface of the cylinder.
- 20 4. An air cushion, comprising an open-ended cylinder, a plunger in the cylinder, a casing inclosing the cylinder, said plunger having a cylindrical recess in its inner end, a cylindrical elastic member constituting an air cushion, a disk in the upper end of said member, rings inside and outside of the said member at its upper end, said disk, said rings and the upper end of said member secured in the recessed end of the plunger, a disk secured in the lower end of the plunger, said first-mentioned disk and plunger having an air inlet port, and a removable plug normally in said port.
- 25
- 30

cushion in the cylinder, one end of said cushion secured in the recess of the plunger, a disk secured in the other end of the cushion, said disk expanding the walls of the cushion and holding the walls of the cushion in contact with the inner face of the cylinder, said cylinder having external screw threads, a cylindrical casing having internal screw threads engaging the threads of the cylinder, said casing inclosing the cylinder, a base on one end of the cylinder extending beyond the same and against which the open end of the casing engages, said casing having a longitudinal bore, and a stem on the plunger projecting through said bore.

4. An air cushion, comprising an open-ended cylinder, a plunger in the cylinder, a casing inclosing the cylinder, said plunger having a cylindrical recess in its inner end, a cylindrical elastic member constituting an air cushion, a disk in the upper end of said member, rings inside and outside of the said member at its upper end, said disk, said rings and the upper end of said member secured in the recessed end of the plunger, a disk secured in the lower end of the plunger, said first-mentioned disk and plunger having an air inlet port, and a removable plug normally in said port.

JOHN J. ISLER.
